UNITED STATES PATENT OFFICE.

HENRY M. YEAGER, OF BUFFALO, NEW YORK, ASSIGNOR TO FEEDERS MANUFACTURING COMPANY, INC., OF BUFFALO, NEW YORK, A CORPORATION OF NEW YORK.

RADIATOR SHUTTER.

Application filed October 14, 1925. Serial No. 62,427.

This invention relates to a shutter for use in connection with radiators which are employed on automobiles for the purpose of cooling the water which is circulated around 5 the engine, the purpose of this shutter being to control the flow of air through the radiator in accordance with the temperature of the weather, it being possible by means of this shutter to either allow a maximum 10 flow of air through the radiator during warm weather and to practically shut off the flow of air during cold weather and to permit a reduced quantity of air to flow through the radiator when the temperature of the weather 15 is moderate.

It is the object of this invention to provide a shutter of this character which is very simple and inexpensive in construction, which can be readily applied to radiators of 20 standard construction, and which can be readily adjusted for controlling the amount of air passing through the radiator to suit the temperature of the weather and which is not liable to get out of order even when subjected to comparatively rough usage.

In the accompanying drawings:

Figure 1 is a rear elevation of one form of shutter embodying my invention.

Figures 2 and 3 are horizontal sections 30 taken on the correspondingly numbered lines in Figure 1 and looking in the direction of the arrows associated with these lines.

Figure 4 is a horizontal section, on an enlarged scale, taken on line 4—4, Fig. 1.

Figure 5 is a rear elevation of the lower 35 part of the shutter frame and the lower end of one of the shutter slats pivotally mounted thereon.

Figure 6 is a fragmentary top plan view 40 of the lower part of the shutter frame shown in Figure 1 with one of the pivot openings, for the pintle at the lower end of one of the slats, in its open position.

Figure 7 is a rear elevation of the same.

Figure 8 is a fragmentary vertical longitudinal section, on an enlarged scale, taken 45 on line 8—8, Fig. 2.

Figure 9 is a fragmentary vertical section, on an enlarged scale, taken on line 9—9, 50 Fig. 1.

Figure 10 is a fragmentary vertical section, on an enlarged scale, taken on line 10—10, Fig. 1.

Figure 11 is a fragmentary perspective 55 view of one of the shutter slats.

Figure 12 is a fragmentary horizontal section taken on line 12—12, Fig. 11.

Figure 13 is a rear elevation of a shutter embodying a modified form of my invention as compared with that shown in 60 Figure 1.

Similar characters of reference indicate like parts throughout the several views.

The main frame of the shutter may be 65 of any suitable form to suit the shape of the radiator with which the same is associated. In the present case this shutter frame is constructed from a single sheet of metal which is stamped so that it is of substantially rectangular form and comprises 70 upper and lower horizontal cross plates 10—11 and vertical side plates 12—12 connecting the corresponding ends of the upper and lower plates 10—11.

The inner edge portion of the top, bottom 75 and side plates of this frame are dished or bulged forwardly so as to form an inner rim all around this edge of the frame. The inner edges of the vertical portions 13 of this rim are provided with inwardly and 80 rearwardly projecting vertical flanges 14, the inner edge of the upper horizontal portion 15 of this rim is provided with an inwardly and rearwardly projecting horizontal flange 16 and the lower horizontal portion 17 of this rim is provided at its inner edge with a horizontal and rearwardly projecting flange 18, said flanges, rim and frame plates being all constructed integrally from 85 a single sheet of metal.

Arranged across the opening within the frame between the flanges 14, 16 and 18 thereof is a plurality of slats or louvers 9 which are pivotally mounted on the frame so that they can be either fully closed or 90 fully opened or arranged in an intermediate or partly open position and thereby enable the air supply to the radiator to be controlled in accordance with the temperature of the atmosphere in which the radiator is 95 to be used. These slats may be variously arranged, but in the construction shown in Figures 1 to 12 each slat is arranged vertically and the several slats are arranged in a horizontal row transversely across the 100 space within the shutter frame. In the preferred construction each of these slats is constructed from a single sheet of metal 105 which is pivotally mounted at its opposite ends on the shutter frame and in the closed 110

position of the several slats each intermediate slat laps at its opposite vertical edges over the corresponding edges of adjacent slats and the outer vertical edges of the extreme slats either engage with or are arranged close to the adjacent inner edge flanges of the frame. In order to produce a practically air tight joint between the several slats when they are thus closed each 10 slat is provided on one of its vertical edges with a vertical groove 19 which is adapted to receive a flange 20 on the opposing vertical edge of an adjacent slat when the several slats are in their closed position, as shown in Figures 2 and 3, thereby excluding the air from the radiator when the shutter is in its fully closed position.

In the preferred construction the sealing groove 19 on each slat is on the rear side 20 thereof and the sealing flange 20 is on the front side thereof whereby any abrasion or marking of these slats when they engage with each other in their fully closed position will not be visible from the front side 25 of the shutter and thereby always maintain the same constantly in a neat and finished appearance.

For the purpose of stiffening these shutter slats each slat is provided midway between 30 its vertical edges with a forwardly projecting vertical bead 21 which is preferably of semi-cylindrical form. The pivots or trunnions 22, 23 whereby each slat is pivotally mounted at its upper and lower ends on the shutter frame are preferably formed integrally of the same sheet of metal from which the slat itself is made. This is accomplished by providing the upper and lower ends of 35 each slat with an extension which is bent into tubular form and preferably concentric with the semi-cylindrical bead 21 so as to practically form a continuation thereof, as shown in Figures 4, 5 and 9 to 12, the joint 40 24 in each of these pivots or trunnions being preferably arranged centrally on the rear side of each pivot.

These pivots or trunnions of the several slats are journaled in bearing openings 25, 50 26 formed in the upper and lower bearing flanges 16 and 18 of the shutter frame, as best shown in Figures 9 to 10. The bearing openings in one of these bearing flanges, for example the bearing openings 25 in the 55 upper flange 16 are complete and unbroken and each of these bearing openings therefore provides a continuous or uninterrupted cylindrical bearing surface in which the respective pivot pin or trunnion 22 turns. The 60 bearing openings in the other bearing flange, in this instance the bearing openings 26 of the flange 18, are each connected with the adjacent edge of the respective flange by means of a slit 27 extending from this opening 65 to said edge of this bearing flange, as shown in Figure 4, whereby one side of

each of these bearing openings 26 may be opened up sufficiently to form an entrance way or throat 29 through which the respective lower pivot pin or trunnion 23 may be moved sidewise into this bearing opening 70 and thereafter this entrance way or throat may be again closed for the purpose of confining the pivot pin or trunnion of the shutter slat therein. As shown in Figure 4 the slit 27 extends tangentially from the 75 pivot opening 16 to the rear edge of the bearing flange 18, thereby forming a retaining lip 28 in rear of the pivot pin 23 which confines the latter in the respective bearing opening. Upon however bending this lip 80 28 downwardly, as shown in Figures 6 and 7 a wide passageway or throat 29 is formed extending from the respective bearing opening 28 to the rear edge of the bearing flange, thereby permitting the lower pivot pin or 85 trunnion on one of the slats to be passed laterally through the throat 29 and then the retaining lip 28 is again bent back into its normal position flush with the remaining 90 portions of the bearing flange 18, as shown in Figure 5 whereby the pivot pin 23 is prevented from moving out from the pivot opening 26. By means of this construction each of the slats may therefore be quickly 95 assembled with the frame by first passing its upper pin or trunnion 22 lengthwise through one of the openings 25 of the upper bearing flange from the under side thereof and then moving the lower pivot pin or trunnion 23 laterally into engagement with one 100 of the lower pivot openings 26, and then retaining these parts in this position by bending the lip 28 into a position across the throat 29. The pivotal mounting of each slat on the frame is therefore effected by 105 these means without the employment of any separate pieces which are detachably connected with the frame and without the use of any solder, riveting or similar fastening, thereby not only simplifying the construction and permitting of manufacturing the 110 shutter at low cost but also avoiding the possibility of any of the parts becoming loose or detached when the shutter is subjected to vibrations or rattling incident to the use of such a shutter on the radiator of an automobile.

Various means may be provided for causing the shutter blades or slats to turn in unison for opening and closing the same 115 either wholly or partly. The preferred means for this purpose are constructed as follows:

The numeral 30 represents an operating arm or crank which projects rearwardly 120 from each slat and is preferably formed integrally therewith at the upper end thereof from a single sheet of metal, as shown in Figure 8. The several operating arms of the group of slats or blades are connected 125

by a shifting bar which in the present construction is preferably constructed in the form of a channel, the hollow side of which faces forwardly and which has a vertical web 31 arranged in rear of the rear ends of the several operating arms 30 and provided with upper and lower walls or flanges 32, 33 which are arranged respectively above and below the several operating arms of the group of shutter slats. Although various means may be provided for pivotally connecting this shifting bar with the several operating arms it is preferable to accomplish the pivotal connection between each arm and the shifting bar by providing one of the flanges of the shifting bar, for instance the upper flange with downwardly projecting teats or projections 34 each of which engages with a recess 35 in the adjacent part of the upper side of one of the operating arms 30 while the lower flange or wall of the shifting bar is provided with a plurality of upwardly projecting teats or projections 36 each of which bears against the even or undented under side of one of the operating arms 30, as shown in Figure 8.

By this means a pivotal connection is produced between the operating arm of each shutter slat and the shifting bar which avoids the use of any bolts, pins, rivets or other separate pivoting member which not only simplifies and reduces the cost of manufacture but also avoids the liability of such separate parts becoming loose. Moreover the present pivotal connection between the shifting bar and the arms of the shutter slats operates with a minimum of friction so that the wear upon the same is unappreciable and therefore maintains the shutter indefinitely in good working condition.

This shifting bar may be moved horizontally in one direction or the other crosswise of the shutter by any suitable means and from any suitable place on the automobile or elsewhere and as such means do not form any feature of this invention no disclosure or description of the same is deemed necessary.

Instead of arranging the shutter slats or blades vertically and in a horizontal row across the space within the shutter frame, as

shown in Figures 1, 2 and 3 the same result is accomplished by arranging the shutter slats or blades in a horizontal position and in a vertical row in the space across the frame, as shown in Figure 13, and since this changed arrangement in no wise alters the construction of the shutter as a whole the same reference characters which are used with reference to the structure shown in Figures 1 to 12 are also employed in the construction shown in Figure 13, it being assumed that the bearing flange at the left-hand side of Figure 13 corresponds to the upper bearing flange of the construction shown in Figure 1 and the bearing flange at the right-hand side of Figure 13 corresponds to the lower bearing flange 18 in Figure 1.

As a whole this radiator shutter is composed of much fewer parts than those heretofore known and used, the same are assembled without the use of any bolts, rivets or other separate fastenings and also without employing any soldering, brazing or the like and the several parts are also so mounted relatively to each other that they work with a minimum amount of friction, thereby enabling this shutter to be manufactured at low cost and to be operated with ease and convenience and without liability of getting out of order.

I claim as my invention:—

A radiator shutter comprising a sheet metal frame provided with bearing flanges, a plurality of slats arranged in a row across the space within said frame and having pintles journaled in said flanges and each slat being provided with an integral arm and each arm being flat on one side and provided with a recess on its opposite side, and a shifting bar of channel form having its walls arranged on opposite sides of said arms and one of said walls being provided with a plurality of pivot teats each of which engages with the recess in one of said arms and the other wall of said bar being provided with a plurality of teats each of which engages with the opposite flat side of one of said arms.

In testimony whereof I affix my signature.
HENRY M. YEAGER.
